UNITED STATES PATENT OFFICE.

JAMES OLIVER, OF SOUTH BEND, INDIANA.

IMPROVEMENT IN CHILLS FOR CASTING MOLD-BOARDS.

Specification forming part of Letters Patent No. 148,236, dated March 3, 1874; application filed February 3, 1874.

To all whom it may concern:

Be it known that I, JAMES OLIVER, of South Bend, in the county of St. Joseph and State of Indiana, have invented certain new and useful Improvements in Chills for Casting Mold-Boards; and I do hereby declare that the following is a full, clear, and exact description thereof, that will enable others skilled in the art to which it appertains to make and use the same, reference being had to the accompanying drawings and to the letters of reference marked thereon, which form a part of this specification, in which—

Figure 1 represents a top view of the cope and water-chamber. Fig. 2 represents a bottom view of the cope and chill. Fig. 3 represents a section through the line $x x$, Fig. 2.

This invention is an improvement on patent granted to me May 2, 1871, in which a pan or chamber is provided, forming a part of the chill, said chill being provided with grooves or creases on its face to conduct away the steam and gas arising from the hot metal coming in contact with the sand and chill, thus allowing the flask to remain in a horizontal position during the operation of casting, while the pan or chamber is filled with and retains the hot water; and it consists in the construction of the pan or chamber, the bottom of which forms the chill, providing the same with arms, the outer ends of which have a suitable shape or form, in order to be attached to the frame of the cope, so that the chill and pan or chamber are rigidly connected to the cope, and at the same time an open space is left in the top of the cope, extending to the bottom of the drag between the outside of the pan or chamber and the frame of the cope, thus allowing the sand to be rammed from the top of the cope, and providing a convenience in forming the

opening through which the molten metal is poured into the mold.

A represents the pan or hot-water chamber, having a shape corresponding with the outline of the mold-board, and the under side of the bottom of said pan forms the chill, the back of which is provided with grooves to allow the steam and gas to pass off when casting, and also provided with perforations *c* for the insertion of the dies *d*, which form the bolt-holes in the cast chilled mold-board. Extending outward from the pan *A*, and cast thereon, are arms *a*, the outer ends *b* of which are of suitable form to fit the cope-frame *B*, and be secured thereto by screws or bolts, thus holding the pan rigid with the cope-frame, and leaving the open sand-space *C* between the outside of the pan and cope-frame, allowing the sand to be rammed from the top, and allowing the opening *D* to be made in any convenient place. The opening *D* communicates with the gate *e*, through which the molten metal is poured into the mold. The opening *D* and gate *e* are formed in the sand *C*. *E* represents the pattern resting on the face of the chill, which is made in the form of the mold-board to be cast. *F* represents the drag of the usual construction, the space *C'* being filled with sand.

Having thus fully described my invention, what I claim as new, and desire to secure by Letters Patent, is—

The open pan *A*, the bottom of which forms the chill, provided with arms *a*, in combination with the cope-frame *B*, substantially as and for the purpose herein specified.

In testimony that I claim the foregoing I have hereunto set my hand.

Witnesses: JAMES OLIVER.
